Des. 229,220

Patented Nov. 13, 1973

229,220

DENTURE CLEANING UNIT

Arthur J. Pulos, Fayetteville, and Paul B. Sweeney, Syracuse, N.Y., assignors to Cooper Laboratories Inc., Wayne, N.J.

Filed Dec. 2, 1971, Ser. No. 204,407

Term of patent 14 years

Int. Cl. D24—01

U.S. Cl. D49—11

FIG. 1

FIG. 2

FIG. 3

FIG. 4

FIG. 5

FIG. 6

FIG. 1 is a front perspective view of a denture cleaning unit embodying our new design with the cover member detached from the remainder of the unit;

FIG. 2 is a front elevation thereof;

FIG. 3 is a rear elevation thereof;

FIG. 4 is a top plan view thereof;

FIG. 5 is a left side elevation thereof, the right side being a mirror image; and

FIG. 6 is a bottom plan view thereof.

We claim:
The ornamental design for a denture cleaning unit, as shown and described.
